(57) **ABSTRACT**

Low carbon dioxide-emitting processes and systems for steam cracking hydrocarbons to produce products such as ethylene are described. The processes and systems involve cracking the feed in a furnace that is configured to burn a hydrogen-rich fuel, which produces less carbon dioxide than methane, which is typically used as fuel for such furnaces. The hydrogen-rich stream can be isolated and recycled from the cracker tail gas.

LOW CO₂ EMISSION ETHANE CRACKER

FIELD OF THE INVENTION

This application relates to steam cracking of hydrocarbon feeds, in particular ethane. More specifically, this application relates to steam cracking systems with low CO₂ emissions.

INTRODUCTION

Ethylene is an important petrochemical intermediate used to make a variety products. Ethylene can be produced from ethane-rich hydrocarbon feedstocks using a process known as steam cracking. During steam cracking, the hydrocarbon feedstock is mixed with steam (known as dilution steam) and heated to cracking temperatures to crack the hydrocarbons in the feed into smaller molecules, producing ethylene and co-products.

An ethane steam cracking plant uses furnaces to heat the ethane and dilution steam used during the cracking reaction. A portion of the waste heat from the furnaces is used to make steam to provide heat for making dilution steam and for other components of the process, such as refrigeration turbines, etc. When the furnace provides sufficient heat for all of the needed steam, the system is said to be in "steam balance."

When the ethane-rich hydrocarbon feed is cracked it produces a cracked product stream that comprises ethylene, as well as other products, such as methane (CH₄), hydrogen (H₂), and carbon dioxide (CO₂). The cracked product stream can be separated into ethylene product and a tail gas stream comprising methane and other components. A portion of the tail gas stream can be used as fuel for the furnace burners. In other words, the cracking reaction can provide some or all of the fuel needed for the burners. When the cracking reaction produces sufficient fuel (in the form of tail gas) to sustain the operation of the burners, the system is said to be in "fuel balance."

In a typical ethane cracker, the tail gas may comprise about 80-85 mol % H₂, with the balance comprising mostly CH₄. When the tail gas is burned in the furnaces, a significant amount of CO₂ is produced because of the CH₄ present in the fuel/tail gas. There is a need to reduce the amount of CO₂ produced during ethane cracking.

SUMMARY

Disclosed herein is a process for steam cracking a feed comprising hydrocarbon feedstock and steam, the process comprising: heating the feed in a furnace to produce a cracked gas stream comprising methane (CH₄), ethylene, and hydrogen (H₂), separating the cracked gas stream into a product stream enriched in ethylene and a tail gas stream that is enriched in CH₄ and H₂, separating the tail gas stream into a CH₄-enriched stream and a H₂-enriched stream that is enriched in H₂, recycling at least a portion of the H₂-enriched stream to the furnace as a fuel stream for furnace burners, mixing the fuel stream with combustion air to form a combustion mixture, and burning the combustion mixture in the furnace burners. According to some embodiments, the hydrocarbon feedstock comprises ethane. According to some embodiments, recycling at least a portion of the H₂-enriched stream to the furnace comprises expanding the H₂-enriched stream in an expander to produce an expanded H₂-enriched stream and recycling the expanded H₂-enriched stream to the furnace as the fuel stream.

According to some embodiments, the H₂-enriched stream has a pressure of greater than 20 barg and the expanded H₂-enriched stream has a pressure of less than 10 barg. According to some embodiments, expanding the H₂-enriched stream drops the temperature of the stream, such that the expanded H₂-enriched stream is colder than the H₂-enriched stream. According to some embodiments, separating the tail gas stream into the hydrocarbon-enriched stream and the H₂-enriched stream comprises cooling the tail gas stream using heat exchange against the expanded H₂-enriched stream. According to some embodiments, none of the hydrocarbon enriched stream is used as fuel for the furnace burners. According to some embodiments, the fuel stream comprises greater than 90 mol % H₂. According to some embodiments, the furnace comprises a radiant section and a convection section. According to some embodiments, the process further comprises preheating the combustion air using heat from flue gas in the convection section before the combustion air is mixed with the fuel stream. According to some embodiments, the combustion air is preheated to at least 350° C. before the combustion air is mixed with the fuel stream. According to some embodiments, the process further comprises heating the feed by heat exchange against the cracked gas stream. According to some embodiments, the process further comprises heating the feed in a feed preheater using heat from flue gas in the convection section. According to some embodiments, the process further comprises heating the feed by heat exchange against the cracked gas stream to at least 350° C. and then heating the feed to at least 650° C. in a feed preheater using flue gas heat in the convection section. According to some embodiments, the furnace fuel demand is satisfied using only the H₂-enriched stream as a fuel stream for furnace burners. According to some embodiments, the process further comprises superheating steam in one or more steam superheaters using heat from flue gas in the convection section.

BRIEF DESCRIPTION OF THE DRAWINGS

FIG. 1 shows a high-level block diagram of a steam cracking process.

FIG. 2 shows a generalized recovery section process for a steam cracking process.

FIG. 3 shows an improved recovery section process for a steam cracking process, which yields a hydrogen-rich stream as a fuel stream for a steam cracker.

FIG. 4 shows an embodiment of a furnace configured for low CO₂ emission steam cracking.

DETAILED DESCRIPTION

Aspects of this disclosure relate to reducing CO₂ emissions from furnace burners used in hydrocarbon steam cracking processes. The disclosure is particularly relevant to ethylene production processes wherein an ethane-rich stream is steam cracked to yield ethylene. FIG. 1 is a high-level schematic of a typical steam cracking process 100. As described above, a feed gas is mixed with steam and cracked in a furnace 102. Heat from the furnace is also used to produce steam. The produced steam may be let down through turbines and then used as diluent steam for the cracking reaction. The steam may also be used as process steam for other aspects of the system, such as refrigeration compressors, etc. The cracker effluent gas (i.e., the cracked gas) from the cracking reaction is provided to a recovery section 104. The recovery section is configured to isolate the ethylene product from the other components of the cracker

effluent. In other words, the recovery section yields an ethylene-enriched stream and an ethylene-depleted tail gas stream. The tail gas stream comprises CH₄, H₂, and small amounts of other components. As described above, some or all of the tail gas stream can be recycled to the furnace and used as fuel for the furnace burners.

FIG. 2 illustrates a more detailed schematic of an embodiment of a portion of the recovery section 104 of a typical ethane cracker. Cracked gas comprising CH₄, H₂, and ethylene (line 202) is progressively cooled and a series of knock-out drums 204 (i.e., drums 204A-204D) are used to knock out ethylene from the effluent stream. Ethylene (and small amounts of methane) knocked out by each of the drums 204A-204D is combined in a combined ethylene-rich stream 206. In illustrated embodiment, the ethylene-rich stream 206 is routed through a cold box 208 (e.g., a plate-fin exchanger), compressed using turbo expander/compressors 210 and 212, and provided from the recovery section as an ethylene recovery stream 214, which may be recycled to the process for recovery. The top streams of each of the knock-out drums is enriched in CH₄ and H₂ and depleted with respect to ethylene. The CH₄ and H₂ exit the system as a single, low-pressure, tail gas stream 214. Typically, the tail gas comprises about 80 to about 85 mol % H₂ with the balance being mostly CH₄.

As described above, the tail gas may be recycled to the furnace as fuel for the burners. Since the tail gas contains a substantial amount of CH₄, the burning of that tail gas in the burners generates a substantial amount of CO₂. The inventors have found that the amount of CO₂ generated by the burners can be reduced by separating the tail gas into a stream that is enriched in H₂ (and depleted in CH₄) and using the H₂-enriched tail gas as fuel for the burners. Specifically, embodiments of the disclosure provide processes for producing a low-pressure H₂-enriched tail gas stream as fuel for the burners in an ethane steam cracking furnace.

FIG. 3 illustrates an embodiment of an improved recovery section process 300 for an ethane cracking process. The cracked process gas from the steam cracker (line 202) comprises H₂, CH₄, and ethylene. The cracked gas enters the illustrated process, typically at a temperature of about -73° C. The cracked gas process stream 202 is cooled in the cold box 308. It should be noted here that the temperatures and pressures in this description of the process 300 are only illustrative of a particular embodiment of the process. Depending on design constraints and considerations, the temperatures/pressures may vary, as will be appreciated by a person of skill in the art. It should also be noted that the cold box 308 may include other hot and cold lines that, in the interest of clarity, are not illustrated here.

The process gas stream 202 is progressively cooled and knock-out drums 302 and 304 are used to remove ethylene from process gas. The cooling temperatures can be configured to manage the approach temperatures in the cold box. According to some embodiments, the temperature of the first knock-out drum 302 may be about -115° C.±10° C. and the temperature of the second knock-out drum may be about -130 to about -145° C. The bottom streams of the knock-out drums 302 and 304, which are enriched in ethylene, can be combined into an ethylene-rich stream 306. The ethylene-rich stream 306 can be recompressed using a turbo expander/compressor 310 to provide an ethylene-rich ethylene recovery stream 312. The top streams of the knock-out drums 302 and 304, which are enriched in CH₄ and H₂ (i.e., tail gas), can be further cooled in the cold box and provided to a third knock-out drum 314. According to some embodiments, the temperature of the third knock-out drum 314 may be about -163° C.±10° C. The top stream 316 from the third knock-out drum 314 is enriched in H₂. The bottom stream 318 from the third knock-out drum 314 is enriched in CH₄.

The temperature of the third knock-out drum 314 determines how much CH₄ is knocked out, i.e., it determines the purity of the H₂ stream. The CH₄-enriched bottom stream 318 is reheated in the cold box and exits the system as a CH₄-rich stream. The H₂-enriched top stream 316 is reheated in the cold box to provide a reheated H₂-enriched stream 322. According to some embodiments, the temperature of the reheated H₂-enriched stream 322 can be about -140° C. and its pressure can be about 20 to about 35 barg. Stream 322 is expanded using the turbo expander/compressor 310 to yield an expanded H₂-enriched stream 324. This drops the temperature and pressure of the expanded H₂-enriched stream 324. For example, according to some embodiments, the temperature of stream 324 may be about -177° C. and the pressure may be less than about 10 barg, for example about 6 barg. The expanded H₂-enriched stream 324 is reintroduced to the cold box 308, thereby providing a cold stream within the cold box capable of providing an adequate temperature approach to effect the separation of CH₄ and H₂ in the knock out drum 314. The expanded H₂-enriched stream 324 ultimately exits the cold box as H₂-rich fuel stream 326, which can be sent back to the furnace to provide H₂-rich fuel for the burners. According to some embodiments, the H₂-rich fuel stream 326 may comprise greater than 90 mol % H₂, or greater than 95 mol % H₂, with most of the remainder comprising CH₄. According to some embodiments, the recovery section process 300 may recover over 90% or over 95% of the H₂ available in the cracked gas process stream.

Whereas the typical recovery section process 104 (FIG. 2) produces a single tail gas stream 214, which comprises both H₂ and CH₄, the improved recovery section process 300 (FIG. 3) splits the tail gas into a hydrocarbon-rich stream (e.g., a CH₄-rich stream) 320 and a H₂-rich stream 326. This allows the H₂-rich stream to be preferentially used as fuel for the furnace burners, thereby reducing CO₂ emissions from the furnace. It should be noted that processes exist in the prior art for isolating H₂ from cracked process gas. Those prior art processes are typically used to isolate H₂ as a commodity gas, not to use as fuel for the burners. The prior art processes typically sacrifice a portion of the H₂ by reinjecting it into the CH₄-rich stream to lower the liquid stream vaporization temperature. As a result, the prior art processes can typically only recover about 80-85% of the available H₂ from the tail gas. Such sacrificial use of a portion of the H₂ is necessary because in the typical process there is not a stream in the cold box having a temperature cold enough to provide a thermal driving force to effect the separation of the CH₄ and H₂. The inventors have discovered that an adequate temperature approach can be achieved by expanding the reheated H₂-enriched stream 322 from a high pressure of about 20 or more barg to a low pressure of about 10 or less barg and then providing the expanded (and thereby cooled) H₂ stream back into the cold box to provide the appropriate temperature approach. It should also be noted here that the expansion/cooling process used in the process 300 would not likely be appropriate in applications where the purpose of isolating the H₂ is to capture it as a product stream. In such H₂ capture processes the H₂-rich stream would typically be provided to a capture operation, such as a pressure swing adsorption (PSA) process. Such processes need a high pressure H₂-rich stream as an input, so dropping the pressure of the stream, as is done in the

process 300, would not be appropriate for H₂ capture. But, since the H₂-rich fuel stream 326 of the process 300 is meant to be burned in the furnace burners, the lower pressure is ideal.

Table 1 shows a comparison of simulations performed using recovery section processes similar to processes 104 and 300. In the simulation, the process 104 generates a single tail gas stream that comprises 84.6 mol % H₂ (14,899 kilograms per hour) and 14.86 mol % CH₄ (20,816 kilograms per hour). Burning the process 104 tail gas in furnace burners provides 689.6 giga-calories per hour of fire duty and produces 88.6 kilograms of CO₂ per giga-calorie produced. The process 300 produces an H₂-rich stream that comprises 14,857 kilograms per hour of H₂ and 6,287 kilograms per hour of CH₄. Burning the process 300 H₂-rich stream in the furnace burners provides 501.1 giga-calories per hour of fire duty and produces 34.7 kilograms of CO₂ per giga-calorie produced.

TABLE 1

recovery section process comparison.				
Process 104		Process 300		
Tail Gas	Mol %	H ₂ -Rich	Mol %	CH ₄ -Rich
H ₂ (kg/h)	14,899	84.60	14,857	94.91
CO (kg/h)	101	0.04	86	0.04
CH ₄ (kg/h)	20,816	14.86	6,287	5.05
C ₂ H ₂ (kg/h)	1,225	0.50	7	0.00
Flow (kg/h)	37,042	100.00	21,238	100.00
Fire Duty (Gcal/h)	689.6		501.1	
kg CO ₂ /Gcal	88.6		34.7	
				231.9

As shown in Table 1, in the simulations, separating the tail gas into a H₂-rich fuel stream and using that stream as fuel for the furnace burners resulted in a greater than 50% reduction in CO₂ produced by the burners. Notice, however, that the available fire duty is also reduced when only the H₂-rich stream is used as fuel. Accordingly, some embodiments of the disclosed steam cracking processes may involve optimizing the system to compensate for the loss of fired duty.

FIG. 4 illustrates an embodiment of a furnace system 400 that is configured to burn H₂-rich fuel, as described above. Temperatures are shown at various locations within the systems, in degrees Celsius (deg C.). It should be appreciated that the illustrated temperatures are only illustrative and other embodiments may use other temperatures.

The furnace system 400 comprises a radiant section (a.k.a., a fire box) 402 where fuel is burnt in burners (not shown) and a convection section 404 where heat from hot flue gas can be recovered for various heating processes, as described below. Fuel is provided for the burners via line 406. As described above, the fuel may comprise a H₂-rich stream isolated from a recovery section process 300 (FIG. 3). Accordingly, the burners should be configured for burning H₂, as is known in the art.

Combustion air is provided to the furnace via line 416. One way of optimizing the system to compensate for the decrease in available fire duty when using only H₂-rich fuel is to preheat the combustion air. In the illustrated furnace system, combustion air is provided by a blower 418 at a temperature of 21° C. According to some embodiments, the air is preheated to a temperature of at least 350° C. The air is preheated in an air preheater 420 (to a temperature of 425°

C. in the illustration) using heat from the flue gas in the convection section. Heating the combustion air reduces the available heat for some of the other heating requirements, such as for heating of process feed and for steam generation that would otherwise be provided by the fire duty of the furnace burners.

Feed, comprising steam and an ethane-rich hydrocarbon enters the furnace system 400 via the feed line 408. In the illustrated embodiment, the feed is first preheated using a feed/effluent exchanger 410 and then is further heated using a feed preheater 412 within the convection section 404. According to some embodiments, the feed preheater may heat the feed to at least 650° C. In the illustrated embodiment, the feed is heated to 710° C. The preheated feed is then passed through the radiant section of furnace via tubes 414A and 414B where the cracking reaction occurs to make product. Two radiant rows are illustrated in the drawing, but it should be appreciated that more or fewer radiant rows may be used.

Once the feeds have passed through the radiant section of the furnace, the product streams are cooled in primary quench exchangers 422A and 422B. The product streams are combined in a combined product stream 424, which is used to preheat the incoming feed stream 408 in the feed/effluent exchanger 410. The product stream exits the system as product output stream 426.

In the illustrated embodiment, the flue gas is used to heat the combustion air in the air preheater 420 and the feed in the feed preheater 412. The flue gas is also used to heat steam in a steam superheater 428 to produce superheated steam (SHS). In the illustrated embodiment, saturated steam is provided to the steam superheater 428 by heating boiler feed water (BFW) from the steam drum 430. The quench exchangers 422A and 422B can be used to heat the BFW to provide the steam, which is subsequently superheated to provide the SHS. In the illustrated embodiment, BFW is provided to the quench exchangers 422A and 422B via line 431a and partially vaporized BFW/steam returns to the steam drum 430 via line 431b. The similar piping to and from the quench exchanger 422A is omitted for clarity. Recall, since the furnace burners only burn the H₂-rich fuel stream instead of burning the entire tail gas stream, the furnace fire duty is reduced. That provides less flue gas heat in the convection section 404 to perform the required heating services.

Another way in which the system 400 can be optimized to accommodate the decrease in fired duty is by balancing the feed preheating duty between the feed/effluent exchanger 410 and the feed preheater 412. In a traditional system without combustion air preheat having a greater fired duty, the primary quench exchangers 422A and 422B may be used to extract a significant amount of heat out of the reacted feed to produce steam. Secondary quench exchangers may also be used to further extract heat from the feed to increase steam generation. But in the system 400, the quench exchangers may be configured to extract less heat, thereby leaving the combined product stream 424 with more heat available to heat the feed stream 408 in the feed/effluent exchanger 410. According to some embodiments, the feed/effluent exchanger 410 may be configured to heat the feed stream to at least 350° C. Notice that the feed stream 408 is heated from 137° C. to 488° C. in the illustrated embodiment. This preheating using the feed/effluent exchanger offloads some of the heating requirement from the feed preheater 412, which, in turn leaves more heat in the convection section available for superheating process steam in the superheater 428 and for combustion air preheat 420.

The inventors have found that using aggressive combustion air preheating and feed heating in the feed/effluent exchanger can reduce the heating requirement of a modeled furnace to within the available fire duty provided by the H₂-rich fuel stream produced using process 300 (Table 1). In other words, the furnace fired duty requirement can be satisfied by using only H₂-rich fuel isolated from the tail gas. This enables the system to operate at less than 30% of the CO₂ emissions of the base (traditional) system.

As described above, according to some embodiments, the furnaces produce substantially less steam. An option to compensate for this and maintain steam balance is to convert one or more of the major compressors from steam turbine driver to electric motor drive. According to some embodiments, power may ideally come from renewable sources to maximize the overall CO₂ emission impact.

Although particular embodiments of the present invention have been shown and described, it should be understood that the above discussion is not intended to limit the present invention to these embodiments. It will be obvious to those skilled in the art that various changes and modifications may be made without departing from the spirit and scope of the present invention. Thus, the present invention is intended to cover alternatives, modifications, and equivalents that may fall within the spirit and scope of the present invention as defined by the claims.

What is claimed is:

1. A process for steam cracking a feed stream comprising a hydrocarbon feedstock and steam, the process comprising:
 pre-heating the feed stream comprising the hydrocarbon feedstock and steam to at least 350° C. in a first heat exchanger to form a first heated feed stream;
 further heating the first heated feed stream with heat from flue gas in a convection section of a furnace to form a second heated feed stream;
 cracking the second heated feed stream in a radiant section of the furnace to produce a cracked gas stream comprising methane (CH₄), ethylene, and hydrogen (H₂);
 generating steam in a second heat exchanger by heating water against the cracked gas stream to produce steam and a partially cooled cracked gas stream;
 passing the partially cooled cracked gas stream to the first heat exchanger to form a cooled cracked gas stream;
 separating the cooled cracked gas stream to produce a product stream enriched in ethylene and a tail gas stream enriched in CH₄ and H₂;

separating the tail gas stream into a CH₄-enriched stream and a H₂-enriched stream, wherein the H₂-enriched stream comprises over 90% of the hydrogen present in the cracked gas stream;

5 pre-heating a combustion air to at least 350° C. in the convection section of the furnace;
 mixing at least a portion of the H₂-enriched stream with the pre-heated combustion air to form a combustion mixture; and
 10 burning the combustion mixture in furnace burners to produce the flue gas.

2. The process of claim 1, wherein the hydrocarbon feedstock comprises ethane.

3. The process of claim 1, further comprising expanding the at least a portion of the H₂-enriched stream in an expander to produce an expanded H₂-enriched stream, and mixing the expanded H₂-enriched stream with the pre-heated combustion air to form the combustion mixture.

20 4. The process of claim 3, wherein the H₂-enriched stream has a pressure of greater than 20 barg and the expanded H₂-enriched stream has a pressure of less than 10 barg.

5. The process of claim 3, wherein expanding the H₂-enriched stream drops the temperature of the H₂-enriched stream, such that the expanded H₂-enriched stream is colder than the H₂-enriched stream.

25 6. The process of claim 5, wherein separating the tail gas stream into the CH₄-enriched stream and the H₂-enriched stream comprises cooling the tail gas stream by heat exchange against the expanded H₂-enriched stream.

7. The process of claim 2, wherein only the H₂-enriched stream is used as fuel for the furnace burners.

8. The process of claim 1, wherein the H₂-enriched stream comprises greater than 90 mol % H₂.

30 9. The process of claim 1, further comprising superheating the generated steam in one or more steam superheaters in the convection section of the furnace to produce a stream of superheated steam.

10. The process of claim 1, wherein heating the first heated feed stream in the convection section of the furnace comprises heating the first heated feed stream to at least 650° C.

11. The process of claim 1, wherein fuel demand of the furnace is satisfied using only the H₂-enriched stream as a fuel for the furnace burners.
